CLAIM

I claim the ornamental design for a cardboard cat ball track wobble toy, as shown and described.

DESCRIPTION

FIG. 1 is a top right perspective view of a cardboard cat ball track wobble toy;

FIG. 2 is a front view of the cardboard cat ball track wobble toy of FIG. 1;

FIG. 3 is a back view of the cardboard cat ball track wobble toy of FIG. 1;

FIG. 4 is a right side view of the cardboard cat ball track wobble toy of FIG. 1;

FIG. 5 is a left side view of the cardboard cat ball track wobble toy of FIG. 1;

FIG. 6 is a top view of the cardboard cat ball track wobble toy of FIG. 1;

FIG. 7 is a bottom view of the cardboard cat ball track wobble toy of FIG. 1;

FIG. 8 is a front view of the cardboard cat ball track wobble toy of FIG. 1 in an alternate position; and,

FIG. 9 is another front view of the cardboard cat ball track wobble toy of FIG. 1 in an alternate position.
